US00D961412S

(12) **United States Design Patent** (10) Patent No.: **US D961,412 S**
(45) Date of Patent: **** Aug. 23, 2022**

(54) **DEVICE FOR MONITORING PROCESS EQUIPMENT**

(71) Applicant: **Alfa Laval Corporate AB**, Lund (SE)

(72) Inventor: **Johnny Ebsen**, Kolding (DK)

(73) Assignee: **Alfa Laval Corporate AB**

(**) Term: **15 Years**

(21) Appl. No.: **35/511,868**

(22) Filed: **Nov. 18, 2020**

(80) **Hague Agreement Data**

Int. Filing Date: **Nov. 18, 2020**

Int. Reg. No.: **DM/212089**

Int. Reg. Date: **Nov. 18, 2020**

Int. Reg. Pub. Date: **May 21, 2021**

(51) LOC (13) Cl. **10-04**

(52) U.S. Cl.

USPC **D10/49**

(58) **Field of Classification Search**

USPC D10/49, 104.1, 106.5–106.6; D8/331, D8/332, 334, 346

See application file for complete search history.

(57) **CLAIM**

The ornamental design for a device for monitoring process equipment, as shown and described.

DESCRIPTION

1. Device for monitoring process equipment

1.1 : Perspective

1.2 : Front

1.3 : Back

1.4 : Right

1.5 : Left

1.6 : Top
